UNITED STATES PATENT OFFICE.

SAMUEL BARUCH, OF NEW YORK, N. Y.

WAISTBAND CONSTRUCTION FOR GARMENTS.

Specification of Letters Patent. Patented Aug. 24, 1915.

1,151,333.

Application filed December 24, 1914. Serial No. 878,925.

To all whom it may concern:

Be it known that I, SAMUEL BARUCH, a citizen of the United States, and resident of New York city, in the county and State of New York, have invented certain new and useful Improvements in Waistband Construction for Garments, of which the following is a specification.

This invention relates to certain improvements in waistbands for garments and is applicable to skirts, petticoats, waists, dresses, as well as other garments.

My invention relates particularly to the means for varying the effective length of the waistband, and by means of my invention I enable the wearer to vary the length of the waistband at will without the use of elastic, gathering strings or the like.

In my improved construction, I employ two slidably connected members which are both preferably formed of metal although other similar material might be employed and these members are so designed that as they slide past each other to shorten the waistband, they are automatically prevented from return movement. The waistband of the garment after the latter has been put on, may be shortened to fit the person and will then remain at that desired length.

Reference is to be had to the accompanying drawings in which similar reference characters indicate corresponding parts and in which one embodiment of my invention is disclosed.

In these drawings, Figure 1 is a perspective view of a portion of a skirt having a waistband constructed in accordance with my invention; Fig. 2 is an elevation of a portion of the waistband on an enlarged scale; Fig. 3 is a central longitudinal section through the parts shown in Fig. 2; Fig. 4 is a perspective view of the coöperating members spaced apart and portions being broken away, and Fig. 5 is a perspective view of a key which may be employed for permitting the release of the parts and the extension of the waistband.

In the specific form illustrated in the accompanying drawings, the waistband carries two members, one of which is slidable along the length of the other and both of which may be partly or entirely concealed between spaced layers of the fabric forming the garment and constituting the waistband proper. As shown, the waistband 10 is formed of a folded-over portion of the

fabric going to make up the body of the garment although it is evident that it might be a separate waistband formed of two spaced layers if desired. The two members forming the essential portions of my invention are both rigidly secured to the waistband. One of the members is in the form of a strip 11, one end of which is rigidly secured to the waistband in any suitable manner, 60 as for instance by an eyelet 12. The strip may be formed of thin flexible sheet metal, celluloid, or any other suitable material and is provided with a series of apertures, transverse ridges, lugs, shoulders or the like 13, the purpose of which will be more fully set forth hereinafter. The body portion of the strip is preferably inclosed within the waistband and is slidable therein by a gathering of the material on the strip. At 70 another point along the waistband and preferably spaced from the fastening 12 a distance substantially equal to the length of the strip 11, is the other member of the device. This is shown in the accompanying 80 drawings as including a base plate 14 secured to the outer surface of the band. The base plate may be secured in any suitable manner. As shown, I employ a second plate 15 disposed upon the inner surface of the 85 band, and two rivets, eyelets or other suitable fastening devices 16 extend through the two plates and through the interposed waistband fabric. The plate 14 is provided with a spring tongue 17 extending outwardly 90 therefrom intermediate the ends of the plate and of such form that it may engage with any one of the apertures or other irregularities along the length of the strip 11.

For holding the strip in proper position 95 in respect to the plate and tongue and for permitting the desired relative sliding movement, the plate carries a guide 18. This guide is in the form of a sheet metal plate with its body portion spaced a slight 100 distance from the outer surface of the plate 14 and having its side edges riveted, seamed or otherwise secured to the side edges of said plate. The distance between the body portion of the guide and the adjacent surface 105 of the plate is such that the strip 11 may slide beneath the guide over the surface of the plate, but is prevented from moving outwardly away from said surface. As it slides through, the spring tongue 17 will 110 come into engagement with the several apertures, shoulders, or the like, on the strip and

after each aperture or shoulder passes the tongue, the strip cannot be moved in the reverse direction. To insure the movement of the tongue up through the aperture, the central portion of the body of the guide may be struck upwardly or embossed so as to leave a slight pocket or chamber 19 into which the end of the tongue may project.

The plate 14 with its spring tongue or catch and the guide may be disposed within the waistband if desired although I have shown them as being secured to the outer surface of the band. With these parts upon the outer surface, the strip preferably passes through spaced apertures in the outer layer of the waistband at opposite sides of the tongue carrying member. Any suitable form of buttonhole or other aperture may serve for this purpose although to prevent the strip from cutting or wearing the fabric at the band where it passes through the outer layer of the waistband, I have shown the apertures as reinforced by metal plates. I provide two of these plates 20 which may be sewed or otherwise secured to the outer layer of the waistband and each plate has a slot 21 therethrough of a width slightly greater than the width of the strip 11. The material of the plate at each side of the slot may be bent inwardly through the slit in the fabric and folded into engagement with the inner surface of the fabric so as to form a binding for the fabric around the opening and to form a guide for the strip 11.

My improved device is adapted for use in connection with custom-made garments in which the waistband is made of somewhat greater length than that required by the average purchaser of that sized garment.

The purchaser, after putting on the garment and fastening the ends of the waistband together by any suitable form of fastening means, such for instance as a snap fastener 23, slides the strip 11 through the retainer member until the waistband has been reduced to the desired size. The spring tongue 17 passes through or enters into the aperture in the strip which, at that time, comes opposite said tongue and the waistband is thus held at the desired effective length.

If at any time it should be desired to further reduce the length of the waistband, it is merely necessary to further force the strip through the retainer member. The device is so constructed that after once having been reduced, the waistband cannot readily be increased in size, but there is preferably provided a key by which the length may be increased in case such increase should be necessary for any reason. In Fig. 5 I have shown a key 24 in the form of a thin strip of sheet metal which may be inserted between the plate 14 and the strip from the right hand end, as shown in Figs. 2 to 4 in-

clusive. By sliding the strip 11 slightly to the left so that the tongue comes between the two apertures 13 and by then sliding in the key until it passes the tongue, the strip may be pulled out while the key covers the tongue and prevents it from entering the several apertures as they pass the tongue. When the band has been increased to the desired length, the key may be readily removed again and the device will operate to prevent further extension.

As previously stated, the device is applicable not only to skirts and petticoats, but also to waists, dresses, and other garments. In using the device in a skirt, the parts are connected to the waistband at such points that the fullness on the strip between the eyelet 12 and the retainer member preferably comes along the center of the back. In other words, the center rear seam 25, if there be such seam, or the center of the rear plait of the skirt comes midway between the secured end of the strip 11 and the retainer member. Preferably, the placket of the skirt comes closely adjacent to the fastener 12 although it is not at all necessary.

In the specific device illustrated, the strip 11 is formed of thin sheet metal although I do not desire to be limited to this specific cross-sectional form. By the term "strip" I wish to include not only the specific form shown, but any other suitable equivalent member which might be a wire or rod round in cross section.

Having thus described my invention what I claim as new and desire to secure by Letters Patent is:

1. A garment waistband formed of two spaced layers of material and having two apertures through the outer layer at spaced points, a retainer member secured to one surface of said waistband between said apertures, and a strip having one end secured to said waistband between said layers and extending out through one aperture past said retainer member and back through the other aperture, said retainer member serving to permit endwise movement of said strip in one direction but prevent endwise movement in the opposite direction.

2. A garment waistband having a retainer member secured thereto, a strip having one end secured to said waistband and having the opposite end extending through said retainer member, said retainer member permitting endwise movement of said strip in one direction but normally preventing return movement, and a key for engagement with said retainer member to permit said return movement.

3. A garment waistband having a plate secured to the outer surface thereof and carrying a spring tongue, a guide secured to said plate and extending over said tongue and a strip having one end secured to said

waistband and having the opposite end unattached to said waistband, the intermediate portion of said strip extending between said plate and said guide and having means for engagement with said spring tongue to normally prevent movement of said strip in one direction.

4. A garment waistband having a retainer secured thereto and including a base plate, a spring tongue and a guide secured to said plate and extending over said tongue and a perforated metal strip having one end secured to said waistband at a point spaced from said retainer and having the opposite end unattached to said waistband, the intermediate portion of said strip extending through said retainer whereby any one of the perforations thereof may receive said spring tongue.

5. A garment waistband having means for detachably securing the ends thereof together and means independent thereof for varying the effective length of said waistband, said means including a flexible strip having one end secured to said waistband and having the opposite end concealed within and slideable along said waistband, and a retainer member secured to said waistband intermediate of the ends of said strip and normally preventing an increase in the effective length of the waistband.

6. A garment waistband formed of two spaced layers of material and having two apertures through the outer layer at spaced

points, a retainer member secured to one surface of said waistband between said apertures and a strip having one end secured to said waistband between said layers and extending through one aperture past said retainer member and back through the other aperture.

7. A garment waistband formed of two spaced layers of material, a strip having one end secured between said layers and having the opposite end slideable along said waistband between said layers and a retainer secured to said waistband presenting a spring tongue for engagement with said strip to normally prevent movement of said strip in one direction in respect to said retainer.

8. A garment waistband having a retainer secured thereto, said retainer presenting a spring tongue, a perforated metal strip having one end secured to said waistband at a point spaced from said retainer and having the opposite end unattached to said waistband, the intermediate portion of said strip extending through said retainer whereby any one of the perforations thereof may receive said spring tongue.

Signed at New York city in the county of New York and State of New York this 21st day of December A. D. 1914.
